ATTACHMENT CLIP FOR CLOTHES HANGERS

Charles L. Allen, Seattle, Wash., assignor of forty-nine one-hundredths to James H. Hodge and Clarence Hodge, jointly

Application July 19, 1938, Serial No. 219,990

5 Claims. (Cl. 24—84)

This invention relates to improvements in clothes hangers, and it has reference to a hanger for both coat and skirt, and more particularly to attachment parts adapted to be used in connection with the common types of coat hangers for the support of a skirt, or garment of a similar nature.

More specifically stated, the present invention resides in the provision of and the application of 10 a pair of clips to the horizontal cross member of an ordinary type of wire coat hanger, for the suspending of a skirt or any other garment of a character that permits it to be supported by the clips. 15 It is the principal object of this invention to provide an improved type of hanger for skirts or other garments, comprising a part that is equivalent to the ordinary wire coat hanger, and a pair of clips that are adapted to be easily applied to and readily adjusted to required or desired spaced relationship along the horizontal cross member of the hanger to coat for suspending of a skirt therefrom, and which clips will be caused to automatically grip and hold themselves at their 20 adjusted positions by reason of the tension, or pull, that is exerted by the garment when properly applied thereto.

It is also an object of this invention to provide a novel form of clip including paired jaws between which the band of the skirt may be slipped easily and without damage thereto, and which will be gripped in a manner whereby it will be safely and securely held.

Other objects of the invention reside in the specific details of construction of a preferred form of device, and of various modifications thereof, also in the mode of application and use of the devices as will hereinafter be fully described.

In accomplishing these and other objects of the invention, I have provided the improved details of construction, the preferred forms of which are illustrated in the accompanying drawings wherein—

Fig. 1 is a view illustrating the present device, particularly the application of the supporting clips to an ordinary type of coat hanger, and also illustrating the manner in which the garment is to be supported thereby.

Fig. 2 is an enlarged detail, illustrating the preferred form of skirt supporting clip used with the device.

Fig. 3 is a cross sectional view, as seen on the line 3—3 in Fig. 2, illustrating the pivoting movement of one of the gripping jaws.

Fig. 4 is a detail, similar to that of Fig. 2, but

illustrating a clip of an alternative form of construction.

Fig. 5 is an end view of the clip seen in Fig. 4, illustrating the pivoting movement of one of the gripping jaws.

Fig. 6 is a view illustrating another alternative form of construction of a clip.

Fig. 7 is a cross sectional view taken on the line 7—7 in Fig. 4.

Referring more in detail to the drawings— 10

In Fig. 1, 1 designates, in its entirety, a garment hanger embodying the present invention, and including what may be an ordinary form of wire coat hanger provided with a horizontal cross member 1a connected by the upwardly covering 15 end portions 1b and 1c to a hook forming portion designated at 1d. While this described part is the preferred form of hanger to be used with other parts included in this invention, it is to be understood that the common wooden form of 20 coat hanger, or even other forms might also be used with equal success, provided that the attached clips, later to be described, are so made as to accommodate the horizontal cross member which, in hangers other than those of wire, are, as 25 a general rule, of greater diameter than the wire 1a of the form of hanger herein illustrated.

Applied to the horizontal member 1a are garment supporting clips which, in Fig. 1, have been designated, respectively, in their entireties by reference numerals 2 and 2', and supported from these clips, is a garment designated at 3. In the present instance, this garment is illustrated as a skirt having a band or belt portion 3a at the upper edge, which is applied to the clip as will presently be explained in detail.

The preferred form of clip is that illustrated best in Fig. 2, wherein 4 designates a horizontally disposed, flat metal bar or plate that is formed at the inner end and at an interval spaced from that end, with supporting hooks 5 and 5a respectively. These hooks, as shown best in Figs. 3 and 5, are designed to hook over the wire 1a. It is also to be noted by reference to Fig. 2 that, intermediate the hooks, the plate 4 is formed 40 with an upwardly bowed part 15c so that it will frictionally and yieldingly press against the horizontal support 1a and thus hold the hooks against being disengaged from the wire and will also provide the necessary amount of friction for preventing the clip from sliding freely along the wire when no garment is being suspended therefrom.

The plates 4 of both clips extend lengthwise of and are disposed directly below the wire 1a and, at their outer ends, are formed with down- 50

55

wardly directed legs 7, which, at their lower ends terminate in spoon shaped heads 1a. These heads form one of the inner jaws of the holding clips.

5 Pivotedly attached by a stud or rivet, as designated at 8, to the outer end portion of each of the plates 4, and near the downturned leg portion 7 thereof, is a spring metal strap 10 having a downturned leg 11, which lies along the leg 7 and, at its lower end, terminates in a spoon shaped head 11a. This head 11a is disposed in what may be considered an opposed relation to the head 1a and together, the heads coact as the jaws of the clip, between which the band portion 15 of the skirt or garment to be supported may be placed in order that the skirt may be held in suspended position.

For purpose of clearer understanding in the claims, the leg 7 of each clip will be referred to 20 as the inner leg or jaw of the clip and the leg 11 will be referred to as the outer leg or jaw.

It will be observed by reference to Fig. 2, that the back portions of the spoon shaped heads 1a and 11a are curved or rounded toward each 25 other, and thus there is provided an entrance mouth, as indicated at 12, opening into the jaws, which provides that the edge or band of the garment may be easily slipped into place between the jaws without necessitating that they be manually gripped and sprung apart. It is also to be observed that the engaging surfaces of these 30 heads are corrugated or knurled, as designated at 13, in order to effect a better gripping and holding action on the garment.

35 In order to provide for an easier application of a garment to the clips, the strap 10 may be rotated about the pivot stud 8 to the position in which it is indicated in dotted lines in Fig. 2, and this throws it to the position as observed in Fig. 3, 40 thus to provide that the band of a skirt or edge of a garment may be first looped or disposed about the inner leg portions 7 of the two clips and then the outer leg portion 11 swung back to gripping position, causing the jaws to automatically 45 adjust themselves to the thickness of the applied garment.

It will here be explained that in applying a garment to the clips 2 and 2', the clips first will be adjusted along the wire 1a to a spaced relationship less than the width of the top of the 50 skirt or garment to be applied. Then the garment is applied about the legs 7 of the clips after the fashion shown in Fig. 1. The clips are moved apart along the wire 1a so that there will be an inward pull exerted on the legs 7 of both 55 clips toward each other. This inward pull causes an upward flexing of the bars 4 between the hooks, resulting in an automatic gripping action effected by the hooks and a binding pressure of 60 the plate 4 against the wire 1a that will hold the clips at the adjusted position and against slipping inwardly toward each other so long as this pull is exerted. However, as soon as this 65 pull is relieved, the clips become free for sliding adjustment.

In Fig. 4 is illustrated an alternative form of clip in which the leg portion 11' of the outer jaw member is bent inwardly and then downwardly so that the pivoting rivet, or bolt, designated at 8a, extends through the downturned portion of that leg and through the leg portion 7' of the clip, instead of through the top or horizontal portion of the plate as seen in Fig. 2. This construction provides the same gripping action by the jaws on the garment as is provided

for in the preferred form of clip but permits a rotation of the leg 11' to a position as illustrated in Fig. 5, for the application of the garment. The gripping action and the supporting action of the jaws is the same, however, as that of the preferred construction and the automatic holding of the clips against slippage on the support 1a is the same. In order to better insure that the clips will not accidentally drop from the supporting hanger when no garment is being suspended thereby, the upwardly bowed part 15b of the plate 4, between the hooks at the point where it engages is provided with the wire 1a, with a depression or groove 15, as indicated in Fig. 7, to seat the under side of the wire 1a therein. 15

Another alternative form or modification of the device is illustrated in Fig. 6 wherein the plate or bar 4" is practically straight across its top and is formed medially of the hooks 5" 20 and 5a with an abrupt hump 16 which yieldingly and frictionally engages against the wire 1a to serve the same purpose as the engaging portion of the plate of the device shown in Fig. 2. In this modification, the leg 11" is illustrated as 25 being pivoted by the rivet 8b directly to the upper end of the leg 7' of the gripping jaw.

Devices of this character may be used for the suspending of various garments merely by engaging parts thereof between the coacting jaws 30 of the clips. However, they are especially useful for the support of skirts, which may be applied as illustrated in Fig. 1, and which, when so applied and the clips then adjusted to that spaced 35 relationship whereby tension is placed thereon, they will be caused to grip and hold their adjustment on the wire 1a.

Devices of this character may be inexpensively manufactured, are easily and readily applied to the type of hanger shown, and will effectively 40 serve their intended purpose.

It is to be recognized that various modifications other than herein illustrated might be made without departing from the spirit of the invention, and therefore, it is not desired that 45 the appended claims be limited only to the clips as herein shown, but that they shall be given an interpretation that is commensurate with the scope of the invention disclosed.

Having thus described my invention, what I 50 claim as new therein and desire to secure by Letters Patent is—

1. An attachment clip for clothes hangers of that kind having a horizontal rod across the base thereof comprising a plate equipped with spaced 55 hooks that are adapted to be hooked over the rod to support the clip, and having a part thereof between the hooks yieldably engaging the rod to prevent the hooks being disengaged.

2. An attachment clip for clothes hangers of 60 the kind having a horizontal rod across the base thereof; said clip comprising a resilient plate adapted to be extended along the underside of the cross rod and formed with spaced supporting hooks for overlying the rod and having a part 65 thereof, between the hooks formed to yieldingly bear against the rod to hold the hooks seated; said plate having paired, depending legs at one end providing inner and outer grip jaws for receiving a garment between them, and said plate being adapted to be put under bowing tension by the pull on the inner jaw, thereby to cant the plate and effect an automatic gripping action of the hooks on the cross rod to hold the clip 70 against slippage while such tension is applied. 75

3. A device as in claim 2, wherein the grip jaws of the clip are yieldably movable to open position to receive a garment between them and have spoon shaped heads, respectively, engaged in back to back relation to receive the garment between them.

4. A device as in claim 2, wherein the outer jaw of said clip has pivotal mounting that permits it to be swung about its pivot out of opposed relationship to the other jaw for reception of a garment between them.

5. An attachment clip for coat hangers of the kind having a horizontal cross rod; said clip com-

prising a metal plate adapted to be extended along and to underlie the cross rod of the hanger and having a garment support at one end turned downwardly at an angle with reference to the plate and having spaced hooks for overlying the 5 rod to support the clip and having a part adapted to bear against the rod at a point between the clips; said plate being adapted to be placed under bowing tension incident to application of a garment to the support to cause bowing of the plate 10 and the hooks to be automatically locked thereby on the rod against slippage.

CHARLES L. ALLEN.
